Attorney-

United States Patent Office.

WILLIAM H. THOMAS, OF SACRAMENTO, CALIFORNIA.

Letters Patent No. 74,630, dated February 18, 1868.

IMPROVED WATER-HEATER FOR BATHS, TUBS, &c.

The Schedule referred to in these Letters Patent and making part of the same.

TO ALL WHOM IT MAY CONCERN:

Be it known that I, WILLIAM H. THOMAS, of Sacramento, in the county of Sacramento, and State of California, have invented a new and improved Steam-Generator; and I do hereby declare that the following is a full, clear, and exact description thereof, which will enable others skilled in the art to make and use the same; reference being had to the accompanying drawings, forming part of this specification.

This invention relates to a new and improved apparatus for heating water and generating steam for various purposes; and the invention consists in the arrangement of a steam or heating-coil within a submerged furnace or fire-box, in such a manner that the same can be connected with different vessels, for various purposes, as for steaming, heating water for baths, washing, &c.

Figure 1 represents a vertical central section of the heater, showing it connected with a reservoir or vessel, and the furnace surrounded by water in a suitable tank.

Figure 2 is a cross-section of fig. 1 through the line *z z*.

Similar letters of reference indicate corresponding parts.

A represents the outer casing or shell of the furnace. B is a coil-pipe in the furnace, which, at its upper end, is connected with the upper portion of a reservoir or vessel in which it is desired to heat the water. The lower portion of the vessel is connected with the bottom or lower end of the coiled tube B. It will be seen that the water in the vessel will be heated by the circulation through the coil.

While the coil is used for steaming purposes, the condensed steam will pass down to the bottom of the coil, while the steam will be discharged from the top, or through the upper pipe. Elastic hose-pipe is used in making these connections, so that steam or heated water may be carried to different vessels without moving the furnace, if desired.

The furnace may be made portable, so as to adapt it to the various purposes for which I design it. By submerging the fire-box, the shell is protected from injury from the intense heat. C represents the grate of the furnace.

To supply the fuel with the necessary oxygen for its proper combustion, a current of air is admitted to and passed down under the grate through the channel D.

It will be seen that the coil B is in contact with the burning fuel, and exposed to the heated products of combustion its whole length; and that, being thus exposed, the current of water which enters its lower end must pass out as steam at its upper end, thus forming a most safe and effective medium for the transmission of heat, combined with a most economical expenditure of fuel.

E represents a water-tank, which is connected with the top of the shell. F is the cap of the furnace, which sets over the top of the shell. G is the chimney-pipe. h is a deflecting-plate, which is attached to and hangs from the cap F, and which extends down into the tank E, which acts as a spark-arrester. The products of combustion, in their upward passage to the chimney-pipe G, impinge against the plate *h*, and the sparks which strike the plate drop from it into the water, and are thereby extinguished, while the smoke passes under the plate and into the pipe G.

The fuel for the furnace is introduced through the cap F by removing the cover J. K represents the hose or water-pipe, which is attached to the upper end of the coil, and L the one at the lower end.

Having thus described my invention, what I claim as new, and desire to secure by Letters Patent, is—

A steam-coil heating-furnace, submerged in water, and supplied with air from the top, and provided with a tank, E, and deflector *h*, all constructed and arranged substantially as herein shown and described.
